CLAIM

The ornamental design for a food container, as shown and described.

DESCRIPTION

FIG. 1 is a top perspective view of a food container, showing our new design.

FIG. 2 is a bottom perspective view of the food container of FIG. 1.

FIG. 3 is a front view of the food container of FIG. 1.

FIG. 4 is a back view of the food container of FIG. 1.

FIG. 5 is a right side view of the food container of FIG. 1.

FIG. 6 is a left side view of the food container of FIG. 1.

FIG. 7 is a top view of the food container of FIG. 1; and,

FIG. 8 is a bottom view of the food container of FIG. 1.

The broken lines depict portions of the food container that form no part of the claimed design.
